UNITED STATES PATENT OFFICE.

JOHN ROGERS FLANNERY, OF PITTSBURGH, PENNSYLVANIA, ASSIGNOR TO FLANNERY BOLT COMPANY, OF PITTSBURGH, PENNSYLVANIA.

STAY-BOLT STRUCTURE FOR BOILERS.

Application filed April 8, 1922. Serial No. 550,696.

To all whom it may concern:

Be it known that I, JOHN ROGERS FLANNERY, a citizen of the United States, and a resident of Pittsburgh, in the county of Allegheny and State of Pennsylvania, have invented certain new and useful Improvements in Stay-Bolt Structures for Boilers; and I do hereby declare the following to be a full, clear, and exact description of the invention, such as will enable others skilled in the art to which it appertains, to make and use the same.

This invention relates to improvements in staybolt structures for boilers,—one object of the invention being to provide, in a flexible staybolt structure, a simple and efficient mounting for the head of the staybolt, which may be quickly and accurately positioned within an opening in the boiler sheet so that no portion of the structure will project beyond the plane of the outer face of the boiler sheet and so that ready access may be had to the removable cap or closure of the mounting.

A further object is to provide a staybolt structure in which the mounting for the head of the staybolt shall have a substantial bearing within the opening in the boiler sheet and at approximately right angles to the axis of the bolt and approximately parallel with the planes of the faces of the sheet, and to permanently secure the mounting to the wall of the opening in the boiler sheet or to the outer face of the sheet in a manner to prevent possibility of displacement or leakage.

With these and other objects in view, the invention consists in certain novel features of construction and combinations of parts as hereinafter set forth and pointed out in the claims.

In the accompanying drawing, Figure 1 is a sectional view illustrating an embodiment of my invention, and Figure 2 is a view of a modification.

In the drawing, the outer sheet of a boiler is represented at 1 and is shown with an opening 2, the inner portion 3 of which is made of less diameter than the outer portion 50 so that an annular shoulder 4 is formed and disposed between the planes of the respective faces of the sheet and preferably nearer the inner face. The annular shoulder 4 is preferably of such width as to provide a broad seat for a bearing sleeve or member

5 and the latter is formed with an annular extension 6 which enters the contracted portion 3 of the opening in the boiler sheet. The bearing sleeve 5 is so proportioned that its outer face will be disposed appreciably 60 inwardly of the outer face of the boiler sheet and said bearing sleeve is formed interiorly with a rounded surface 7 which forms a seat for the rounded head 8 of a staybolt 9. The opening in the sleeve outwardly beyond the seat portion for the staybolt head, is enlarged somewhat, forming a shoulder 10 and this enlarged portion of the opening in the sleeve has a threaded wall to receive an externally threaded cap or closure 70 11,—the latter being so proportioned that when in position on the bearing sleeve with its inner edge seated against the shoulder 10, (or on a washer 12 on said shoulder) its outer face will not 75 project beyond the plane of the outer face of the boiler sheet but may be flush with the same.

When the parts shall have been assembled (either before or after the closure 11 shall 80 have been applied to the bearing sleeve), the bearing sleeve will be permanently secured in place by welding, said bearing sleeve, as a rule, being permanently secured in place by welding to the wall of the opening in the boiler sheet (as indicated at 13), prior to inserting the bolt.

In the embodiment of my invention shown in Figure 2, the enlarged portion 14 of the opening in the boiler sheet is made shallower 90 than in the construction shown in Figure 1 and provides a shoulder 15. The bearing member 16 passes through the opening in the boiler sheet and its enlarged portion 17 forms a shoulder 18 to rest upon the shoulder 15. The enlarged portion 17 of the bearing member projects beyond the outer face of the boiler sheet and is secured in place by a weld 19 between the outer face of the portion 17 of the bearing member and 95 the outer face of the boiler sheet. The bearing member is provided in its inner portion with a seat 20 for the head 21 of a staybolt 22, and a removable closure 23 is provided for the bearing member.

Having fully described my invention what I claim as new and desire to secure by Letters-Patent, is:—

1. In a staybolt structure, the combination with a boiler sheet provided with an opening 110

having portions thereof differing in diameter whereby an annular shoulder is formed between the planes of the respective faces of the sheet, of a mounting for a stay-
5 bolt having parts different in diameter located in said opening, the part of said mounting having the greater diameter resting upon said annular shoulder in the boiler sheet and welded to the latter, a staybolt
10 having a head seated in said mounting, and a removable closure engaging said mounting over the head of the staybolt.

2. The combination with a boiler sheet having an opening and formed therein with
15 an annular shoulder, of a bearing sleeve mounted on said shoulder so that its position will be confined between the planes of the respective faces of the sheet, means permanently uniting said bearing sleeve to the
20 wall of said opening, said bearing sleeve having a seat therein for the head of a staybolt, a staybolt having a head mounted on

said seat, and a closure connected with said bearing sleeve over the head of the staybolt.

25

3. In a staybolt structure, the combination with a boiler sheet having an opening, of a mounting disposed in said opening and located inwardly of the planes of the respective faces of the boiler sheet, said mounting comprising a bearing sleeve welded to the wall of said opening and having an interior seat for the head of a staybolt, a removable cap or closure attached to said sleeve over the seat therein, and a staybolt 30 provided with a head mounted on the seat within said sleeve.

30

In testimony whereof, I have signed this specification in the presence of two subscribing witnesses.

JOHN ROGERS FLANNERY.
